METAL VAPOR RECTIFIER

Application filed June 27, 1928, Serial No. 288,749, and in Germany June 30, 1927.

It has been found by experience that in vapor rectifiers the mercury vapors formed at the cathode have to be kept as far as possible from the anodes. When the power is increased, more mercury will be of course vaporized, so that the surface of the wall of the metal vessel will no longer suffice for absorbing the increased lost heat. The means provided hitherto for this purpose in rectifiers of smaller power, such as anode sleeves and the like, no longer meet the requirements which increase with the increase in power. For this reason it is necessary to provide a larger cooling surface in the interior of the rectifier vessel for condensing the mercury vapor. Various arrangements for condensing the mercury vapor by means of separate cooling bodies having a large surface located in the interior of the rectifier body have already been proposed. Thus it has been suggested to provide within the anodes arranged in a circle a system of cooling coils or a double-walled cylindrical insertion or several such insertions arranged concentrically. All condensation arrangements hitherto proposed have the great disadvantage that the total cooling surface of the cooling body cannot be fully utilized. The reason for this is that the mercury vapor rising in the form of a brush from the cathode is deflected from its natural direction when impinging against the cooling surfaces of the known cooling bodies, so that, owing to the consequent reduction in velocity, there is an accumulation of vapor. Hence, with concentric cylindrical cooling bodies the vapor condenses at the lower part of the cooling body and at the wall surface lying in the outlet passage, the remainder of the surface of the same is not utilized for cooling and condensation, that is to say the vapor does not come in contact with it.

According to the present invention this drawback is overcome by the provision in the interior of the rectifier vessel within the circle of anodes of a double-walled, closed hollow body for the reception of cooling liquid, which is freely accessible on all sides and has its outer wall cylindrical and its inner wall arranged in radial folds, so that mer-

cury vapor rising like a brush from the cathode impinges without being deflected in its direction in its natural course against the cooling body.

A constructional example of the present invention is shown in the accompanying drawings in Fig. 1 in longitudinal section and in Fig. 2 in cross-section on the lines B—B and A—A respectively.

a is the rectifier vessel with the cathode *b* and the circularly arranged anodes *c*. The condensation arrangement consists of a hollow body *d* filled with cooling liquid and having radially and inwardly directed cooling pockets *e*. The cooling pockets extend close up to the cylindrical outer wall of the cooling body, leaving an unobstructed central outlet passage. The cooling body is positioned within the vessel so as to be freely accessible on all sides, such that there is communication between the anode space and the cooling dome or condensation space. As will be seen from Fig. 1, the cooling pockets are longitudinally displaced in the direction of flow of the vapor with respect to the outer wall of the cooling body, so that their lower edges converge conically inwards. The cooling liquid enters at *f* and escapes at *g*.

With the constructional form of the cooling body according to the present invention, through the entire cooling surface of the cooling pockets being utilized in a suitable manner, the necessary cooling and condensation of the mercury vapor for metal vapor rectifiers for large powers is fully realized. The bush-like stream of vapor impinges in its natural course on the surface of the cooling pockets and passes without deflection into the outlet passage. The condensed mercury collects at the lower edge of the cooling body and can be returned in a known manner to the cathode by means of separate collecting devices.

What I claim is:

1. A mercury vapor rectifier containing a ring of anodes and within said ring of anodes a double-walled closed hollow body for the reception of cooling fluid, the outer wall of the said body being cylindrical and the inner

wall so arranged in radial folds as to form cooling pockets for the mercury vapor.

2. A mercury vapor rectifier as claimed in claim 1 wherein the said cooling pockets are displaced longitudinally with respect to the outer wall in the direction of the vapor stream so that their lower edges converge conically inwards.

3. A mercury vapor rectifier as claimed in claim 1 wherein the said cooling pockets are displaced longitudinally with respect to the outer wall in the direction of the vapor stream so that their lower edges converge conically inwards, the said inner wall leaving an unobstructed central passage between its inwardly projecting folds.

In testimony whereof I have signed my name to this specification.

OSKAR SEITZ.
